CLAIM

The ornamental design for a strobe adapter for magnetic disc still camera, as shown and described.

DESCRIPTION

FIG. 1 is a front elevational view of a strobe adapter for magnetic disc still camera showing my new design;
FIG. 2 is a rear elevational view thereof;
FIG. 3 is a top plan view thereof;
FIG. 4 is a bottom plan view thereof;
FIG. 5 is a left side elevational view thereof;
FIG. 6 is a right side elevational view thereof; and,
FIG. 7 is a perspective view thereof.

*FIG. 1**FIG. 2**FIG. 3**FIG. 4**FIG. 5**FIG. 6**FIG. 7*
